(57) CLAIM

The ornamental design for a lipstick case, as shown and described.

DESCRIPTION

FIG. 1 is a front view of a lipstick case showing the new design, the rear view being a mirror image thereof.

FIG. 2 is a right side view thereof.

FIG. 3 is a left side view thereof.

FIG. 4 is a top view thereof.

FIG. 5 is front, top and left side perspective view thereof; and, FIG. 6 is a one point front perspective view thereof, with the two parts of the lipstick case separated from one another. In the drawings, the broken lines showing the interior portions of the lipstick and the top portion of the cap form no part of the claimed design.
